UNITED STATES PATENT OFFICE.

GEORGE STOCKHAM EMERICK, OF NAZARETH, PENNSYLVANIA.

GRINDING-MILL.

964,224.

Specification of Letters Patent. Patented July 12, 1910.

Application filed October 18, 1907. Serial No. 398,044.

To all whom it may concern:

Be it known that I, GEORGE STOCKHAM EMERICK, citizen of the United States, residing at Nazareth, in the county of Northampton and State of Pennsylvania, have invented certain new and useful Improvements in Grinding-Mills, of which the following is a specification.

The object of my invention is to provide a simple and efficient machine for grinding and screening coal, limestone, cement clinker, &c., said machine having provision whereby access may be readily had to either the grinding or the screening mechanism, and whereby the discharge of hard substances by centrifugal force from the grinding mechanism to the screen is obviated.

The invention consists in the novel construction and combinations of parts herein-
20 after fully described and claimed.

Figure 1 is a vertical section of a grinding and screening machine embodying my invention. Fig. 2 is a sectional plan view thereof, as on the line 2—2, of Fig. 1. Fig. 25 3 is a sectional plan view of the screening mechanism, as on the line 3—3, of Fig. 1.

4 designates a frame work, the upper portion of which supports a casting 5 having a circular depression 6 therein for the reception
30 of the ground material. Resting upon the top of the casting 5 and surrounding the depression 6 therein, is a circular frame 7, provided with a cover 8. The casting 5, frame 7, and cover 8 are secured together
35 by suitable bolts 9, and they inclose a chamber 10, in which the material is ground.

Supported in the lower portion of the frame work 4, is a bearing 11, in which is journaled the lower end of a central, vertically arranged shaft 12, provided with a driving pulley 13. The upper end of the shaft 12 extends into the chamber 10 and through a bearing 13 in the casing 5. Arranged within the chamber 10 and secured to the upper end of the shaft 12, is the hub of a circular, rotatable grinding member 14, provided with a horizontal portion 15, from which extends an upwardly and outwardly inclined portion 16. The inner face of the inclined portion 16 is provided with a hard metal ring 17, forming a grinding surface.

Resting normally in contact with the grinding surface of the ring 17, is a series
55 of grinding rollers 18 which are carried by outwardly and upwardly inclined shafts 19,

the axes of which are parallel to the grinding face of the ring 17. The shafts 19 extend outwardly through openings 20 in the cover 8, and are supported in bearings 21. 60 The upper ends of the shafts 19 are provided with grooves 22, into which extend rings 23, which are secured between the bearings 21 and caps 24 thereon. These rings 23, engaging the grooves 22, prevent 65 longitudinal movement of the shafts 19.

Each bearing 21 is arranged between two arms 25 which rise from the cover 8, and each bearing 21 is provided with projecting pivot studs 26 which extend into openings 70 in the arms 25, thus pivotally supporting the bearings 21, shafts 19, and rollers 18, in a manner to permit the rollers 18 to move toward and from the grinding surface of the ring 17, the openings 20 being large 75 enough to permit such movement.

Pivotaly connected to each bearing 21 below the pivot stud 26, is the inner end of a rod 27 which extends outwardly through an opening in a lug 28 projecting from the 80 frame 7. The outer end of each rod 27 is screw-threaded for the reception of the internally threaded hub of a hand wheel 29, between which and the lug 28 is interposed a spring 30, surrounding the rod 27. The 85 springs 30, bearing against the lugs 28 and the hubs of the hand wheels 29, tend to force the rods 27, and therewith the bearings 21, outwardly, and thus hold the rollers 18 yieldingly in contact with the grinding 90 surface of the ring 17, from which they may be moved on the pivot studs 26 in opposition to the springs 30. By adjusting the hand wheels 29, the pressure of the rollers 18 against the ring 17 may be nicely 95 regulated.

Supported upon the cover 7 and extending centrally therethrough, is a tube 31, the upper end of which is provided with a flaring or funnel-shaped inlet 32, into which 100 the material to be ground is introduced and from which it passes through the tube 31, and is deposited upon the grinding member 14.

Arranged below the chamber 10 and surrounding the shaft 12, is a circular screen 33, which is supported at its upper end by a flange depending from the casting 5.

The casting 5, or floor of the depression 6, is provided with openings 34 therein, to afford communication between the chamber 10 and the interior of the screen 33, suitable 110

blades 35 being provided on the bottom of the member 15 for delivering the ground material within the depression 6 to the openings or passageways 34. The bottom of 5 the screen 33 is provided with a floor or plate 36, upon which the ground material which does not pass through the screen is deposited.

Leading from one side of the screen 33 is. 10 a passageway or chute 37, through which the material deposited upon the floor 36 is discharged from the screen. This passageway 37 may lead to a conveyer or any suitable opening or discharge. Secured to the 15 shaft 12 above the floor 36, is a plate 39 carrying blades 40 which move the material upon the floor 36 to and discharge it through the passageway 37. Mounted upon the shaft 12 are collars 41, from which project fan 20 blades 42 within the screen 33, the purpose of which is to force the ground material through the screen as it falls from the openings 34 during the rotation of the shaft 12.

Surrounding the screen 33 is a cylindrical 25 casing 43 which is supported by a flange projecting from the casting 5 and providing a chamber 48 surrounding said screen. The bottom of the casing 43 is closed by a floor or plate 44, arranged below the floor 36, and 30 leading from the floor 44 is a discharge passageway 45, which may lead to a conveyer or any suitable point of discharge.

Secured to the shaft 12 between the floors 36 and 44, is a plate 46 carrying blades 47 35 adapted to move the material deposited upon the floor 44 to the discharge passageway 45.

The operation may be briefly described as follows:—The material to be ground is introduced to the grinding member 14 through 40 the tube 31, and power is applied to the pulley 13 to rapidly rotate the shaft 12 and therewith the grinding member 14. The material to be ground passes from the horizontal portion of the member 14 by centrifugal action to and between the grinding surface of the ring 17, and the rollers 18. During the rapid rotation of the member 14 the rollers 18 are turned with or upon the shafts 45 19 by contact with the ring 17 and the material to be ground, and thus effect the crushing or grinding operation. After the material has been ground, it passes by centrifugal force over the top of the inclined portion 16 of the member 14, and falls by 50 gravity into the depression 6, from which it is discharged through the openings 34, into the screen 33. As the ground material falls through the screen 33, it is blown by the blades 42 against the screen and the finer particles of the ground material pass through the screen into the chamber 48, while the coarser particles fall upon the floor 36 and are, by the action of the blades 55 40, discharged through the passageway 37.

The finer particles, after passing through the screen 33 into the chamber 48, fall upon the floor 44, and are moved by the blades 47 to and discharged through the passageway 45.

By the construction and operation hereinbefore described, it will be seen that the grinding mechanism cannot become choked for any cause whatsoever, for the reason that the ground material may pass on 75 through the openings 34 and passageway 37 to a point of discharge even when no material is passing through the screen 33, which sometimes happens due to the dampness of the material clogging the screen and 80 due to other causes. Further, it will be seen that by the construction and arrangement of the parts no hard substances such as pieces of iron, &c., should they find their way into the grinding mechanism, will be 85 thrown therefrom by centrifugal force against the screen 33 to injure the same, but will pass down through the openings 34, and being unaffected by the air from the fans 42, will fall upon the floor 36 and 90 pass out through the passageway 37. This arrangement, whereby the screen is thus protected, is an important feature of my invention.

I claim:—

1. In a grinding mill, the combination of the frame, walls forming a grinding chamber having a bottom, a substantially vertically-arranged circular screen below said chamber and communicating therewith, 100 said screen having a floor portion closing the bottom thereof, walls forming a passageway leading from the interior of the screen, a casing surrounding the screen in spaced relation thereto, said casing having a floor portion closing the bottom thereof, walls forming a passageway leading from the interior of said casing, a centrally arranged shaft extending through the floor portion of the grinding chamber and into 105 the grinding chamber and into the screen, a grinding member carried by said shaft within the grinding chamber, a second grinding member coacting with the first named grinding member, and means carried by said shaft for causing the ground material to pass through said screen and into said casing.

2. In a grinding mill, the combination of the frame, walls forming a grinding chamber having a bottom, a substantially vertically-arranged circular screen below said chamber and communicating therewith, said screen having a floor portion closing the bottom thereof, walls forming a passageway leading from the interior of the screen, a casing surrounding the screen in spaced relation thereto, said casing having a floor portion closing the bottom thereof, walls forming a passageway leading from the interior of the screen, a 120 casing surrounding the screen in spaced relation thereto, said casing having a floor portion closing the bottom thereof, walls forming a passageway leading from the interior of the screen, a 125 casing surrounding the screen in spaced relation thereto, said casing having a floor portion closing the bottom thereof, walls forming a passageway leading from the interior of the screen, a 130 casing surrounding the screen in spaced relation thereto, said casing having a floor portion closing the bottom thereof, walls forming a passageway leading from the in-

terior of said casing, a centrally arranged shaft extending through the floor portion of the grinding chamber and into the grinding chamber and into the screen, a grinding member carried by said shaft within the grinding chamber, a second grinding member coacting with the first named grinding member, means carried by said shaft for causing the ground material to pass through said screen and into said casing, means carried by said shaft for discharging material deposited upon the floor portion of the

screen through the passageway leading from the interior of the screen, and means carried by said shaft for discharging material deposited upon the floor portion of the casing through the passageway leading from the interior of the casing. 15

In testimony whereof I affix my signature in presence of two witnesses.

GEORGE STOCKHAM EMERICK.
